UNITED STATES PATENT OFFICE.

FREDRICK S. DICKINSON, OF NEW YORK, N. Y.

LOOM.

1,188,418.

Specification of Letters Patent. Patented June 27, 1916.

Application filed November 14, 1913. Serial No. 801,001.

To all whom it may concern:

Be it known that I, FREDRICK S. DICKINSON, a citizen of the United States, and resident of New York, in the county and State 5 of New York, have invented certain new and useful Improvements in Looms, of which the following is a specification.

This invention relates to looms, and it has special relation to an improved loom mechanism for weaving a tubular endless fabric adapted to be employed as the body fabric in the carcass or casing of pneumatic wheel 10 tires for automobiles or the like.

The object of my invention is to provide 15 an improved loom which will be adapted to effectively weave a tubular endless fabric of the character above set forth, in such shape as to conform to the normal contour of the tire, without stretching, pulling, 20 packing, or otherwise distorting the weave, thus maintaining a uniform tension on each and every strand of both warp and woof threads throughout the body of the completed fabric, and thereby retaining the 25 initial strength of every strand in the woven mass.

A further object of my invention is to provide an improved loom mechanism for producing a fabric, such as that just described, either in single or multiple plies, 30 with the multiple plies either interwoven in a unitary homogeneous fabric or woven in separate relationship.

A further object of my invention is to 35 provide a simple and improved loom mechanism, which will in its leading features be adapted for effective weaving under usual or general conditions, which will be positive and convenient in operation, and 40 which will furthermore possess advantages in point of adaptability to various forms of weaving, effectiveness, and general efficiency.

In the drawings—Figure 1 is a side elevation illustrating one embodiment of my invention—Figure 1 is a side elevation illustrating one embodiment of my invention, parts being broken away and parts being shown in section. Fig. 2 is a transverse vertical sectional view of the mechanism as illustrated in Fig. 1. Fig. 3 is a top or plan view of the mechanism as illustrated in Fig. 1, taken on a horizontal plane below the top heddle mechanism. Fig. 4 is a detail side view, partly in section, of the mechanism for tripping the means for carrying the warp prior to 55 the weaving of the woof. Fig. 5 is a detail side view, partly in section, of the latch

mechanism for bringing into position the means for supporting the fabric after the weaving of the woof. Fig. 6 is a detail side view, partly in cross-section, of the means 60 for retaining the warp in position during the weaving of the woof. Fig. 7 is a detail side view, partly in section, of the means for controlling the movement of the shuttle, and of parts of the heddle mechanism in their 65 relation to the warp. Fig. 8 is a detail side elevation, partly in section, of part of the heddle mechanism as shown in Fig. 1. Fig. 9 is a detail edge view of the means carried at the ends of the spokes of the warp reel, 70 for carrying the warp and for supporting the fabric after the weaving of the woof. Fig. 10 is a detail side view, partly in section, illustrating the operation of the shuttle and showing parts of the heddle mechanism 75 in their relation to the warp. Fig. 11 is a detail edge view of the means for supporting the fabric after the weaving of the woof, showing in dotted lines a completed tire carcass or casing fabric thereon. 80

Corresponding parts in all the figures are denoted by the same reference characters.

Referring to the drawings, 1 designates an upright framework arranged to carry all the operating parts of the loom mechanism. 85 From said framework extends a laterally-projecting fixed shaft, 2, upon the outer end of which is revolubly mounted a reel, 3, which in its general structure is of wheel form and is constituted by a series of radial 90 spokes, 4, as will be hereinafter described. The hub, 5, of the reel 3 is keyed, as at 6, to the extended hub, 7, of a gear wheel, 8, revolubly mounted upon the shaft, 2, and said gear 8 meshes with a pinion, 9, carried 95 by a revoluble stud shaft, 10, having its bearing, as at 11, in the framework 1. Said pinion is fixed to a ratchet wheel, 12, which is actuated by a pawl, 14, carried by a rocking lever, 15, loosely mounted upon the 100 shaft 10, and said lever is actuated by a yoke or connecting rod, 16, carrying at its outer end a roller, 17, coöperating with the periphery of a cam disk, 18, carried by a driving shaft, 19, having its bearing, as at 105 20, upon the framework 1, said driving shaft passing through a guide slot, 21, in the outer end of the yoke 16. Said driving shaft 19 suitably carries band wheels or pulleys, as at 22, by which motion may be imparted 110 from any suitable source of power. By means of the preferred mechanism just de-

scribed, a revoluble motion is imparted to the reel 3 in progressive step action, the yoke 16 and the lever 15 and pawl and ratchet 14 and 12 being actuated in one step movement with each revolution of the cam 18 and the driving shaft 19.

The radial spokes of the reel 3 are each of telescopic construction, the projective section, 23, of said spokes being normally maintained in extended outward position with relation to the main socket or base section, 24, by compression springs, 25, carried by said socket section. The projecting section or member 23 of the spokes carries the means for carrying the warp prior to the weaving of the woof and the means for supporting the fabric after the weaving of the woof. Such first mentioned means, as herein shown, consists of a ring, 26, of arc shape in cross section, which is pivotally mounted, as at 27, upon the outer end of the spoke section 23 and is provided at its periphery with a series of projecting guide pins, 28, for retaining the threading of the warp in position as it is carried by the reel prior to the weaving of the woof. The spread of said arc rings 26 is preferably greater than the diameter of the tubular fabric as woven, so that in their approach to the position for the weaving of the woof the warp threads are spread in the manner indicated in Fig. 3.

It will be understood that the number of pins or teeth 28 forming the comb for holding the warp threads is regulated by the number of warp threads it is desired to employ, and that the warp is initially wound between said teeth and around the entire reel in a continuous length, the relative size of the arc rings 26 and their teeth 28 being such that the proper circumference and position is given to each thread section of the warp to form the required shape and size of the endless tubular fabric it is desired to weave, due allowance being made for the "take up" in the weaving of the woof and for compensating for the percentage of crimp it is desired to put in the warp.

A circular ring, 29, in band form, is also pivotally mounted, as at 30, upon the outer end of the spoke sections 23, the office of which ring is to support and carry the fabric after the weaving of the woof. Said rings 29 have their pivot intermediate of the pivotal mounting of the arc rings 26, and are therefore adapted to swing within the latter, as more clearly shown in Fig. 9, and said rings 29 are adapted in size to the shape and cross section of the inner diameter of the woven tubular endless fabric.

The rings 26 and 29 are pivotally mounted in transverse relation to the axis of the reel, and constitute the peripheral portion thereof by which the warp and also the

woven fabric are carried during the revoluble step movement of the reel. In said latter movement, it is necessary that the warp be freed from said carrying means during the weaving of the woof and the action of the heddles, and it is therefore necessary 70

to trip said warp-carrying means from operative position prior to the weaving of the woof, and also to afterward bring the rings 29 into operative position for supporting 75

the fabric after the weaving of the woof. In the preferred construction for said tripping action, the arc rings 26 are provided with a projecting lug, 31, and the circular rings 29 are also provided with a projecting 80

lug, 32, these lugs being arranged in fulcrum position with relation to the pivots of the rings and being adapted to be simultaneously engaged by projecting trip lugs, 33 and 34, respectively, carried upon a mov- 85

able trip member, 35. The trip lugs 33 and 34 are brought into action, during the movement of the reel, at a point a suitable distance in advance of the shuttle mechanism, to throw the rings 26 and 29 upon 90

their pivots and permit their movement to the position as shown in Fig. 1, to remove the arc ring from the warp before the warp moves up to the shuttle mechanism. The carrying member 35 for the trip lugs 33 95

and 34 is slidably mounted in a bearing, as at 36, at the projecting end of a lever, 37, pivotally mounted, as at 38, upon the framework 1, and beyond said sliding bearing the member 35 has its end pivoted, as at 39, 100

to the projecting end of another lever, 40, arranged at right angles to the lever 37 and having its fulcrum, as at 41, upon said lever 37 (see Fig. 4). Said lever 37 carries, at a 105

point adjacent the fulcrum of the lever 40, a roller, 42, bearing against the edge of a crown cam wheel, 43, mounted at right angles to the pivotal movement of the lever 37 and fixed to the revoluble shaft 10 which is actuated by the pawl and ratchet mechanism hereinbefore described in connection 110

with the driving means for the reel 3. The roller 42 is held in yielding engagement with relation to the cam 43 by a suitably mounted spring, 44, exerting its tension 115

against the lever 37. Thus, in operation, the revolution of the cam 43 permits the lever 37 to move outwardly (to the left, from the position shown in full lines as illustrated in Fig. 4), when the recess, 45, in the cam edge 120 receives the roller 42, thus bringing the trip lugs 33 and 34 in alinement with the lugs 31 and 32 of the rings 26 and 29.

In the position just stated, the lugs 33 and 34 are adapted to engage the lugs 31 and 32 125 when the trip member 35 is projecting in its slidable bearing, and to effect this movement the free end of the lever 40 is provided with a roller, 46, adapted to engage the edge of a cam, 47, mounted in parallel relation to 130

the cam 43 and upon the driving shaft 19, whereby when the lever 40 is carried outwardly by the movement of the lever 37 it will be actuated by the cam 47 to move the trip member 35 in its slideable bearing and bring the lugs 33 and 34 in engagement with the lugs 31 and 32, and thus trip the rings 26 and 29 and permit them to move to the position shown in Fig. 1 to disengage the arc ring 26 from the warp. After the action just described, the lever 37 returns to normal position (see Fig. 4), by further movement of the cam wheel 43, and thus carries the lever 40 to normal position with its roller 46 beyond the plane of engagement with cam 47, which movement returns the trip lugs 33 and 34 to their normal position, as shown in full lines in Fig. 4, out of the path of movement of the succeeding spokes 4 of the reel 3. After the rings 26 and 29 are tripped under the operative action just described, and while the spokes of the reel are passing in their path of movement beneath the shuttle mechanism, a roller, 48, mounted at one side of the projective spoke section 23, enters into engagement with a cam track, 49, suitably mounted upon the framework 1 and having an irregular curvature whereby as said roller, 48 travels in engagement with said cam track the spoke section 23 is telescoped within the socket or base spoke section 24 until the terminus of the cam track is reached at a point beyond the location of the shuttle mechanism, when the spoke section 23 returns to outward normal projective position by action of spoke spring 25 (see Figs. 1 and 2). The outer ring portions 26 and 29 of the spokes are thus, after they are tripped from engagement with the warp, held down away from the shuttle mechanism, during the passage of the spoke beneath the latter, and the ring 29 is then returned to outward position at a point a short distance beyond the location of the shuttle mechanism. The downward position of the ring portions 26 and 29 is limited by the engagement of a lug, 50, with a stop pin 51, projecting laterally from the spoke section 23, as shown in Figs. 1 and 9.

The return of the ring 29 to outward position, after it has passed beyond the location of the shuttle mechanism, is effected by a latch mechanism which engages said ring and returns it to upward position in a radial plane with relation to the spoke, thus bringing the ring within the woven fabric after the latter has passed beyond the shuttle mechanism, in which position said ring will support the woven fabric upon the reel during the further step movement thereof, as illustrated in Fig. 1. In the preferred construction, the latch mechanism for this purpose comprises a pivoted catch, 52, adapted in its movement to engage the lug 32 of the ring 29, said catch having its pivot or ful-

crum, as at 53, upon a block, 54, slidably mounted on a rod or arm, 55, the pivotal movement of the catch being governed by a spring, 56, and a stop-pin, 57, respectively carried by the block 54. Said sliding block 53 carries a projecting pin, 58, having a bearing in a slot, 59, at the end portion of one arm of a bell-crank lever, 60, which is suitably fulcrumed upon the framework, and has its other arm pivotally connected with a link or connecting rod, 61, which at its other end is pivoted to another bell-crank lever, 62, suitably fulcrumed upon the framework. Said latter lever is pivotally connected with a yoke bar, 63, slotted to provide a sliding bearing upon a shaft, 64, suitably journaled in the framework, and carrying a roller, 65, engaging the periphery of a cam disk, 66, carried by said shaft 64. Thus, by operation of the cam 66 and the connections as above described, the bell-crank lever 60 is actuated to slidably move the block 54 upon its guide rod 55 and thus cause the operative action of the catch 52 to throw the ring 29 into position to support the woven fabric. The latch mechanism also has a lateral movement so that the sliding block 54 carrying the catch 52 and the rod or arm 55 will be intermittently operated to bring the same to a position in which it will clear the spokes 4 of the reel 3 during the revoluble movement of the latter. The preferred mechanism for this purpose comprises a lever, 67, carrying the rod or arm 55 and suitably fulcrumed upon the framework 1, said lever carrying at its free end a roller, 68, engaging with a lateral projection, 69, on the cam wheel 43 of the tripping mechanism by which the rings 26 and 29 are brought to downward position from engagement with the warp as hereinbefore described. Thus, by action of the cam wheel 43, the lever 67 is operated in a lateral movement to move the latch mechanism out of the path of the spokes of the reel 3 and to return the same to operative position, the movement being suitably timed with relation to the operative action of the other parts of the general mechanism. The lever 67 is of suitable angular contour to properly span in operative position the space between the rod or arm 55 and the actuating cam wheel 43.

A brake band, 70, is preferably suitably arranged with relation to the extended hub 7 of the gear wheel 8 by which the reel 3 is driven, to effect proper tension with relation to the movement of the warp under the reel action and to prevent the gear 8 and the reel mechanism which it drives from running ahead of the ratchet movement by which said gear is actuated.

The warp is supported, at a point immediately preceding the shuttle mechanism, by a mandrel, 71, of circular contour conforming to the inner diameter of the fabric to

be woven, said mandrel being supported upon a bracket, 72, projecting from the framework 1, and correspondingly a mandrel, 73, is mounted upon a bracket, 74, and 5 is operatively located, at a point immediately beyond the shuttle mechanism, to support the woven fabric. Operatively located, respectively with relation to these fixed mandrels, are clamping bands, 75-76, of 10 corresponding circular contour, the band 75 of the mandrel 71 being adapted to receive the spread of the warp threads (see Fig. 3) and clamp the same in proper relative position for the weaving of the woof, while the 15 band 76 of the mandrel 73 is adapted to correspondingly clamp the woven fabric, this clamping operation being maintained intermittently during the operation of the shuttle mechanism and the weaving of the 20 woof. The clamp 75 is held under spring tension, to effect proper tension on the warp threads during the process of weaving, and the clamp is adapted to be automatically released against the tension of the spring to 25 permit the passage of the warp in the successive step movements of the reel 3. In the preferred construction for effecting the operation just described, the clamp is divided into two approximately semi-circular 30 sections by a hinge joint, as at 77, one of said sections having its free end in substantially fixed relation to the bracket 72 and the free end of the other section being pivotally connected to a rod, 78, slidably mounted 35 in said bracket. Said rod 78 carries a laterally-projecting pin 79, to which is connected a governing coiled spring, 80, extending from a fixed part of the framework 1, the action of which spring is to draw the clamp 40 75 to normal clamping position with relation to the mandrel 71 (see Fig. 6). The pivotal connection between the rod 78 and the section of the clamp 75 is preferably detachable, the pivot being for this purpose 45 constituted by a removable pin, 81, whereby the clamp can be disconnected from the rod 78 and lifted off the warp to enable the threading of the latter when desired. The automatic release of the clamp 75, to permit 50 the step movement of the warp under the revolute action of the reel, is effected by a mechanism which, in the preferred construction, comprises a bell-crank lever, 82, fulcrumed, as at 83, upon the bracket 72, one 55 end of said lever being in operative connection with the slidable rod 78 by engagement with the projecting pin 79 thereof, while to the other end of said lever is pivotally connected a rod, 84, carrying a roller, 85, en- 60 gaging the periphery of the cam disk 66 upon the shaft 64. The movement of the mechanism, to effect the release of the clamp 75 against the tension of the spring 80 and 65 to permit the return of the clamp to normal position under action of said spring, is suit-

ably timed with relation to the action of the general operating mechanism whereby the reel 3 is advanced in its step movements. The other clamp 76 of the mandrel 73, which 70 operates with relation to the woven fabric, 75 is of a construction corresponding to that just described with relation to the clamp 75, said corresponding construction comprising a hinge joint for the clamp and a slidable rod connected with the free end 75 of one of the clamp sections and controlled by the tension of a spring and a bell-crank lever in operative connection with said rod, the rod 84 whereby the bell-crank lever 82 of the governing mechanism of the 80 clamp 75 is operated being extended (as indicated at 86, Fig. 6) to a pivotal connection with the bell-crank lever of the mechanism governing the clamp 76, whereby the action of the cam disk 66' for the release of the 85 warp clamp 75 is simultaneously communicated to the clamp 76 for the action thereof to release the woven fabric coincident with the step movement of the reel 3.

The shuttle mechanism is arranged intermediately with relation to the mandrels 71 and 73, and comprises a bracket, 87, projecting from the framework 1 and extending up within the path of movement of the woven fabric, said bracket carrying at its upper 90 end a suitably journaled stud shaft, 88, arranged in the plane of the line of movement of the woven fabric and axially with relation to the segmental transverse contour thereof (see Figs. 1 and 2). Said stud shaft 95 88 carries a bevel gear, 89, meshing with a bevel gear, 90, carried at the upper end of a universal-joint shaft, 91, suitably journaled, as at 92, in a bracket projecting from the framework, and carrying at its lower 100 end a pinion, 93, engaged by a rack bar, 94, moving in a suitable guide, 95, carried by the framework 1. Said rack bar 94 extends to a pivotal crank connection, as at 96 (see Fig. 1), with a crank disk, 97, carried by 105 a shaft, 98, suitably journaled in the framework 1, whereby said rack bar is reciprocated in reverse movements to impart a corresponding movement to the universal-joint shaft 91 and the stud shaft 88 with which 110 it is in geared connection.

The stud shaft 88 carries the means for actuating the shuttles, which means consists of a magnetic shoe, 99, carried upon an arm, 100, fixed to the end of said stud shaft opposite the bevel gear 89 and projecting laterally with respect to the shaft, whereby in the oscillating movement of the shaft the magnetic shoe travels in reverse movements in a circular path corresponding to the circular-transverse contour of the fabric to be woven. The arm carrying the magnetic shoe is preferably of telescopic or adjustable construction, to effect the operation of the magnet in proper relation to the fabric mass 115 120 125

which is being woven and in equi-distant relation to the inner transverse curvature of the fabric mass.

It will be understood that my improved loom mechanism is adapted for the weaving of tubular endless fabrics of various transverse sizes, by adjustment or adaptation of the position of the magnetic shoe 99 and of the size of the rings 26 and 29 and of the mandrels 71 and 73 and their clamps, and that in the employment of the loom for weaving this type of fabric, for instance, a tubular endless fabric to conform to the normal contour of the body fabric for the car-cass or casing of pneumatic wheel tires for automobiles or the like, the fabric is left open at the inner side of its tubular transverse contour, where the edges are formed for the engagement of the tire casing with the clencher wheel rims, and that this continuous opening accommodates the portions of the shuttle-operating mechanism which project within the fabric mass and also permits the operation of the rings 26 and 29 as hereinbefore described. In the preferred construction, the bracket 87 carries receptacles, as at 101—101, respectively at the termini of the reverse movements of the shuttles, for the reception of the shuttles at the end of their movements for weaving the woof threads (see Fig. 7). In Fig. 10, I have illustrated one type of construction for the adjustable relation of the magnetic shoe 99 to its carrying arm 100, the magnet being in this construction provided with an extension, 102, received by the arm 100 and secured in adjusted position by means of a set screw, 103.

In my present improvements, the purpose and operative function of the magnetic shoe 99 is to control the movement of the shuttle and effect its travel in the proper path of the reverse movements to lay the woof threads through the sheds as formed by the heddles. The shuttles are therefore constructed of steel or other material subject to magnetic action, and are in effect operative as armatures controlled and moved by the magnet 99 in the reciprocating operation of the latter, by means of the mechanism as hereinbefore described, whereby the shuttles are carried through the shed formed by the movement of the heddles in the usual manner of weaving with warp and woof or filling threads. The shuttles, as shown at 104, may be in the main of any usual or adapted construction operating in the usual manner to carry and feed the woof or filling threads.

A batten mechanism is provided to properly close in or pack in position the woof threads and enable the laying of the same in lines radiating from the axis of the reel. Said batten, as shown at 105, carries reeds, 106, and is operative within the fabric mass at a point immediately preceding the shut-

tle mechanism, and the batten with its reeds is carried by a downwardly-projecting arm, 107, connected at its lower end with a hub, 108, which is loosely mounted on the extended hub 7 of the gear wheel 8. Said arm 107 is of suitable angular contour to properly span the space between the batten 105 and the hub 108, and at a point intermediate of its ends it is pivotally connected, as at 109, with a rod or yoke, 110, the outer end of which has a slotted bearing, as at 111, upon the shaft 19 which carries the cam disk 18'. Said rod 110 carries a roller, 112, engaging the periphery of the cam disk 18', whereby the rod will be reciprocated under action of the cam and impart an oscillating movement to the batten to effect the action of the reeds to properly pack the woof threads. In this oscillating movement the arm 107 which carries the batten has a bearing on its hub 108 which in turn bears upon the extended hub 7 of the gear wheel 8. The operation of the batten mechanism is suitably timed with relation to the action of the other general mechanism, and is properly adjusted to the number of plies which are to be comprised in the woven fabric and the interweaving of the woof threads to connect the plies in a unitary homogeneous woven fabric. For instance, under the four ply conditions as indicated in Fig. 10, the woof threads are packed into position by the reeds of the batten after each cycle of movements of the shuttle to make the four ply connections of the woof thread. Under the circular conditions of weaving, as indicated, in packing the woof threads there will be, say, 25% more open space between the threads at the outer peripheral portion of the fabric than at the inner portion, there being approximately 25% difference in the circumference of the outer and inner diameters, whereby there is produced a stronger rivet at the outer peripheral portion than on the sides, there being a gradual decrease in the number of threads to the inch on the radial plane from the axis.

The heddle construction may be of any adapted type operative in substantially the usual manner to enable the laying by the shuttle of the woof threads through the sheds as formed by the heddles. I have herein illustrated a heddle mechanism, in its co-operative relation to the action of the shuttle mechanism and as adapted to the operative action of the general mechanism of my improved loom. In this preferred construction of the heddle mechanism, the warp is threaded through the terminal spring eyes, as at 114, of the heddle rods, 115, which are guided in a segmental frame, 116, suitably mounted upon and projecting from the framework 1 and surrounding the warp at a point immediately preceding the shuttle mechanism, whereby the heddle rods 130

are held in proper alignment at an angle of approximately 90° to each warp thread and the warp threads are laid to the desired tubular contour of the fabric. In the illustration as shown in Figs. 10 and 8, there are eight sets of heddle rods, as adapted for the weaving of the fabric in a unitary homogeneous mass constituted by four directly connected plies. The heddles are actuated in their up and down movement, to form the shed through which the shuttle passes, by means of segmental cam rails, 117, which are concentrically arranged with relation to the segmental frame 116 and are provided in sets at opposite sides of the set of heddle rods, there being four such cam rails in each side set, as shown in Figs. 8 and 1. Thus, a cam rail is provided for each heddle rod of the set of eight, and the inclined surface, as at 118, of the rail engages fingers, as at 119, projecting laterally at the top ends of the heddle rods, whereby under the lateral movement of said cam rails an upward and downward movement will be imparted to the heddle rods. The lateral movement of the cam rails is effected by cam disks, 120, carried by a shaft, 121, suitably journaled in the framework 1. A cam disk, as at 120, is provided for each cam rail 117, and these cam disks respectively have an operative connection with their respective cam rails by means of a connecting rod or yoke, 122, having a slotted end, 123, embracing the shaft 121 and forming a guide bearing thereon, said rod also carrying a roller, as at 124, engaging the periphery of the cam disk, 120, and being pivotally connected, as at 125, to one end of a lever, 126, the other end of which has a pivotal connection, as at 127, with a rod, 128, slidably mounted in lateral relation to the cam rail 117 and carrying the same in the reciprocal movement of said rod. The levers 126 are suitably fulcrumed, as at 129, and the slidable rods 128 have their bearings, as at 130, in a supplementary framework, as at 131, mounted upon the main framework 1. It will be understood that the operation of the cams 120 and the general mechanism for actuating the cam rails 117 in their lateral movement to operate the heddle rods 115, is suitably timed with relation to the operation of the other parts of the general loom mechanism.

The various shafts as hereinbefore described, carrying the cam mechanisms and other operative elements, are in operative connection by means of a train of gears, 132, as indicated in Figs. 1 and 2, whereby the movement of the main drive shaft is communicated to cause the simultaneous movement of the various shafts as comprised in the general loom mechanism, and that said shaft connections are so geared that the operation of the various shafts and the mechanisms

controlled thereby will be timed to produce the proper sequence of operation of the various different mechanisms in their respective office or function as hereinbefore described.

I do not herein specifically claim the shuttle-actuating means controlled by a magnet, said shuttle mechanism in itself and in its general application to looms of divers constructions being reserved for a separate application for patent.

The operation and advantages of my improved loom mechanism will be readily understood by those skilled in the art to which the invention appertains. The step movement of the reel 3 gives the necessary travel to the warp threads after each movement or cycle of movements of the shuttle to weave the woof threads. For instance, in producing an endless tubular fabric of a single ply type, the mechanism will be timed to advance the woof threads after each movement of the shuttle in the segment of the tubular fabric, whereas in weaving such fabric with multiple plies, as indicated in Fig. 10, the step movement of the reel to advance the warp threads will be after the shuttle has completed the cycle of movements in the segment of the tubular fabric necessary to lay a single woof strand through the warp threads of each of the multiple plies.

It will be understood that my improved loom mechanism is adapted for weaving endless tubular fabrics in either single ply or multiple plies, and for weaving the totally-mounted peripheral means for carrying plies in separate condition or with the respective plies interwoven to produce a unitary homogeneous fabric mass, and also that the general features of improvement are adapted for effective and advantageous employment in looms adapted for the weaving of various other types of fabric. For instance, the feature of the magnetic control of the shuttle action, and other features as comprised in the improved mechanism, may be employed in looms of various types for weaving either flat or tubular fabrics.

I do not desire to be understood as limiting myself to the detail construction and arrangement of parts as herein shown and described, as it is manifest that variations and modifications therein may be resorted to, in the adaptation of my invention to varying conditions of use, without departing from the spirit and scope of my invention and improvements. I therefore reserve the right to all such variations and modifications as properly fall within the scope of my invention and the terms of the following claims.

Having thus described my invention, I claim and desire to secure by Letters Patent:

1. In a loom for circular weaving, a reel mechanism comprising means projective pe-

- peripherally for carrying the warp, and means for withdrawing said first mentioned means from engagement with the warp as the latter passes up to the shuttle mechanism.
5. 2. In a loom for circular weaving, a reel mechanism comprising means projective peripherally for carrying the warp, means for drawing said first mentioned means toward the axis of the reel and from engagement with the warp as the latter passes up to the shuttle mechanism, and means for retaining said warp-carrying means in such withdrawn position during its passage by and beyond the shuttle mechanism.
10. 3. In a loom for circular weaving, a reel mechanism comprising means projective peripherally for carrying the warp and means projective peripherally for sustaining the woven fabric, means for withdrawing said peripherally-projective means from operative position as the warp moves up to the shuttle mechanism, and means for moving said fabric-sustaining means into projective operative engagement with the woven fabric as the latter moves from the shuttle mechanism.
15. 4. In a loom for circular weaving, a reel mechanism comprising means projective peripherally for carrying the warp and means projective peripherally for sustaining the woven fabric, both said means being conjointly mounted in projective position, means for drawing both said means toward the axis of the reel as the warp moves up to the shuttle mechanism, whereby the warp-carrying means is withheld from operative position, and means for returning the fabric-carrying means to projective position in engagement with the woven fabric after the latter passes beyond the shuttle mechanism.
20. 5. In a loom for circular weaving, a reel mechanism comprising means peripherally projective for sustaining the woven fabric, means for retaining said sustaining means from projective position during the passage thereof with relation to the shuttle mechanism, and means for bringing said sustaining means into projective position and engagement with the woven fabric after the latter moves beyond the shuttle mechanism.
25. 6. In a loom for circular weaving, a reel mechanism comprising pivotally-mounted means projective peripherally for sustaining the woven fabric, means for retaining said sustaining means in turned down position upon its pivot during the passage thereof with relation to the shuttle mechanism, and latch mechanism operative with relation to said sustaining means to bring the latter upwardly into projective position and in engagement with the woven fabric after the latter has passed beyond the shuttle mechanism.
30. 7. In a loom for circular weaving, a reel mechanism comprising a pivotally-mounted ring projective peripherally for sustaining the woven fabric, means for tripping said ring and holding the same in turned down position when out of operation, and means for tripping said ring and bringing the same to projective position in engagement with the woven fabric when the latter passes beyond the shuttle mechanism.
35. 8. In a loom for circular weaving, a reel mechanism comprising a pivotally-mounted ring peripherally projective and provided at its periphery with a series of projecting guide pins for retaining the warp, and means for tripping said ring to downward position and disengagement from the warp as the latter moves up to the shuttle mechanism.
40. 9. In a loom for circular weaving, a reel mechanism comprising a pivotally-mounted ring peripherally projective and provided upon its periphery with a series of guide pins for retaining the warp and a pivotally-mounted ring peripherally projective within said first mentioned ring, means for simultaneously tripping both said rings to downward position and disengagement from the warp as the latter moves up to the shuttle mechanism, and means for tripping said inner ring and returning the same to projective position and engagement with the woven fabric after the latter moves beyond the shuttle mechanism.
45. 10. In a loom for circular weaving, a reel mechanism comprising conjointly means projective peripherally for carrying the warp and sustaining the woven fabric, and means for drawing the warp-carrying means from operative position as the warp moves up to the shuttle mechanism and for bringing the fabric-sustaining means into operative position and in engagement with the woven fabric after the latter passes beyond the shuttle mechanism.
50. 11. In a loom for circular weaving, a reel mechanism comprising radial spokes carrying at their outer ends pivotally-mounted peripheral means for carrying the warp and sustaining the woven fabric, and means for operating said pivotal peripheral means to bring the same into and out of operative position during the movement of the reel.
55. 12. In a loom for circular weaving, a reel mechanism comprising radial telescopic spokes carrying at their outer ends pivotally-mounted peripheral means for carrying the warp, means for tripping said warp-carrying means upon its pivot to bring the same to downward position, and means for telescoping said spokes during the movement of the reel.
60. 13. In a loom for circular weaving, a reel mechanism comprising radial telescopic spokes carrying at their outer ends pivotally-mounted peripheral means for sustaining the woven fabric, means for telescoping said spokes and releasing the same

- 28
- during the movement of the reel, and means for tripping said pivotal fabric-sustaining means to bring the same into projective position and in engagement with the woven fabric.
- 5 14. In a loom, means for feeding the warp in a step movement, a mandrel for sustaining the warp, and spring-controlled clamping means for binding the warp upon said mandrel during the periods between the step movements of said warp-feeding means, said clamping means comprising a plurality of sections tensionally maintained in their relative operative status by said 10 spring-control.
- 15 15. In a loom, means for feeding the warp in a step movement, a mandrel for sustaining the warp, clamping means for binding the warp upon said mandrel during the 15 periods between the step movements of said warp-feeding means, said clamping means comprising a plurality of sections, tensional means for governing the action of said clamping sections and maintaining their 20 relative operative status, and means operating to intermittently actuate the clamping means against said tensional means to relatively 25 separate the clamping sections and release the warp coincident with the step movements of said warp-feeding means.
- 30 16. In a loom for circular weaving, means for feeding the warp in a step movement, a mandrel of curved or segmental contour and conforming to the inner diameter of the 35 fabric to be woven, a clamping band of corresponding curved or segmental contour extending around said mandrel for binding the warp thereon, said clamping band comprising a plurality of sections, and means 40 for controlling the relative operative status of said sections.
- 45 17. In a loom for circular weaving, means for feeding the warp in a step movement, a mandrel of curved or segmental contour and conforming to the inner diameter of the fabric to be woven, a clamping band of corresponding curved or segmental contour extending around said mandrel for binding the warp thereon, said clamping band comprising a plurality of sections, and means 50 for tensionally controlling said sections and maintaining their relative operative status.
- 55 18. In a loom for circular weaving, means for feeding the warp in a step movement, a mandrel of curved or segmental contour and conforming to the inner diameter of the fabric to be woven, a clamping band of corresponding curved or segmental contour extending around said mandrel for binding the warp thereon, said clamping band being 60 constituted by hinged sections, and means for intermittently opening said clamping band to release the warp coincident with the step movements of said warp-feeding means.
- 65 19. In a loom for circular weaving, means for feeding the warp in a step movement, a mandrel of curved or segmental contour and conforming to the inner diameter of the fabric to be woven, a clamping band of corresponding curved or segmental contour extending around said mandrel for binding the warp thereon, said clamping band being constituted by hinged sections, and means for tensionally controlling the closing of said sectional clamping band to clamp the warp, 70 and means operating against said tensional means to intermittently open the clamping band to release the warp coincident with the step movements of said warp-feeding means.
- 75 20. In a loom, means for carrying the woven fabric in a step movement, a mandrel for sustaining the woven fabric, clamping means for binding the woven fabric upon said mandrel, and means for intermittently releasing said clamping means coincident with the step movements of said fabric-carrying means.
- 80 21. In a loom, means for carrying the woven fabric in a step movement, a mandrel for sustaining the woven fabric, and tensionally-controlled clamping means for binding the woven fabric upon said mandrel during the periods between the step movements of said fabric-carrying means, said clamping means comprising a plurality of sections maintained in their relative 85 operative status by said tensional-control.
- 90 22. In a loom, means for carrying the woven fabric in a step movement, a mandrel for sustaining the woven fabric, clamping means for binding the woven fabric upon said mandrel during the periods between the step movements of said fabric-carrying means, said clamping means comprising a plurality of sections, means for 95 tensionally controlling said sections and maintaining their relative operative binding action, and means acting against said tensional means for intermittently operating the sections of the clamping means to release the woven fabric coincident with the step movements of said fabric-carrying means.
- 100 23. In a loom for circular weaving, means for carrying the woven fabric in a step movement, a mandrel of circular or segmental contour and conforming to the inner diameter of the woven fabric, clamping means of corresponding circular or segmental contour for binding the woven fabric upon said mandrel during the periods between the step movements of said fabric-carrying means, said clamping means comprising a plurality of sections, and means for controlling the relative operative status 105 of said sections.
- 110 24. In a loom for circular weaving, means for carrying the woven fabric in a step movement, a mandrel of circular or segmental contour and conforming to the inner 115 diameter of the woven fabric, clamping means of corresponding circular or segmental contour for binding the woven fabric upon said mandrel during the periods between the step movements of said fabric-carrying means, said clamping means comprising a plurality of sections, and means for controlling the relative operative status 120 of said sections.
- 120 25. In a loom for circular weaving, means for carrying the woven fabric in a step movement, a mandrel of circular or segmental contour and conforming to the inner 125 diameter of the woven fabric, clamping means of corresponding circular or segmental contour for binding the woven fabric upon said mandrel during the periods between the step movements of said fabric-carrying means, said clamping means comprising a plurality of sections, and means for controlling the relative operative status of said sections.

diameter of the woven fabric, a clamping band of corresponding circular or segmental contour for binding the woven fabric upon said mandrel, said clamping band being constituted by hinged sections, and means for tensionally controlling the action of said sectional clamping band to release the woven fabric coincident with the step movements of said fabric-carrying means.

10 25. In a loom for circular weaving, means for carrying the woven fabric in a step movement, a mandrel of circular or segmental contour and conforming to the inner diameter of the woven fabric, a clamping band of corresponding circular or segmental contour for binding the woven fabric upon said mandrel, said clamping band being constituted by hinged sections, tensional means for controlling the binding action of said sectional clamping band, and means operating against said tensional means for intermittently opening said sectional clamping band to release the woven fabric coincident with the step movements of said fabric-carrying means.

20 30 35 40 45 50 55 60 65 70 75 80 85 90 95 100 105 110 115 120 125 130

26. In a loom, means for feeding the warp in a step movement and for carrying the woven fabric in a corresponding step movement, a mandrel for sustaining the warp, a mandrel for sustaining the woven fabric, and clamping means operating respectively with relation to said mandrels to bind the warp and woven fabric thereon during the periods between the step movements of said warp-feeding and fabric-carrying means.

27. In a loom, means for feeding the warp in a step movement and for carrying the woven fabric in a corresponding step movement, a mandrel for sustaining the warp, a mandrel for sustaining the woven fabric, clamping means operating respectively with relation to said mandrels to bind the warp and woven fabric thereon during the periods between the step movements of said warp-feeding and fabric-carrying means, and means for simultaneously operating both said clamping means to intermittently release the warp and woven fabric coincident with the step movements of the warp-feeding and fabric-carrying means.

28. In a loom, means for feeding the warp in a step movement and for carrying the woven fabric in a corresponding step movement, a mandrel for sustaining the warp, a mandrel for sustaining the woven fabric, clamping means operating respectively with relation to said mandrels to bind the warp and woven fabric thereon during the periods between the step movements of said warp-feeding and fabric-carrying means, means for tensionally controlling the action of both said clamping means, and means for simultaneously operating

both said clamping means against their tensional action and intermittently to release the warp and fabric coincident with the step movement of said warp-feeding and fabric-carrying means.

29. In a loom, means for feeding the warp and for carrying the woven fabric in a step movement, a mandrel for sustaining the warp, a mandrel for sustaining the woven fabric, clamping means operative with relation to said respective mandrels to bind the warp and to bind the woven fabric thereon during the periods between the step movements of said warp-feeding and fabric-carrying means, and a shuttle mechanism extending and operative intermediately of said mandrels.

30. In a loom, means for feeding the warp and for carrying the woven fabric in a step movement, a mandrel for sustaining the warp, a mandrel for sustaining the woven fabric, clamping means operative with relation to said respective mandrels to bind the warp and to bind the woven fabric thereon during the periods between the step movements of said warp-feeding and fabric-carrying means, a shuttle mechanism extending and operative intermediately of said mandrels, and means for simultaneously operating said respective warp and fabric clamping means to release the warp and fabric intermittently and coincident with the completion of the respective movements of the shuttle mechanism to weave the woof and the step movements of said warp-feeding and fabric-carrying means.

31. In a loom for circular weaving, a reel mechanism comprising means projective peripherally for carrying the warp, means for advancing said reel mechanism in step movements, a mandrel for sustaining the warp, clamping means for binding the warp upon said mandrel during the periods between the step movements of said reel mechanism, shuttle mechanism extending and operative at a point in advance of said mandrel, and means for withdrawing said peripherally-projective means from engagement with the warp as the latter moves up to said mandrel.

32. In a loom for circular weaving, a reel mechanism comprising means projective peripherally for carrying the woven fabric, means for advancing said reel mechanism in step movements, a mandrel for sustaining the woven fabric, clamping means for binding the woven fabric upon said mandrel during the periods between the step movements of said reel mechanism, shuttle mechanism extending and operative at a point in rear of said mandrel, means for retaining said fabric-carrying means from projective position during the passage thereof with relation to the shuttle mechanism, and means

- for bringing said fabric-carrying means into peripherally-projective position and in engagement with the woven fabric after the latter moves beyond said mandrel.
33. In a loom for circular weaving, a reel mechanism comprising means projective peripherally for carrying the warp, means for advancing said reel mechanism in step movements, a mandrel for sustaining the warp, a mandrel for sustaining the woven fabric, clamping means operative with relation to said respective mandrels for clamping the warp and the woven fabric thereon during the periods between the step movements of said reel mechanism, shuttle mechanism extending and operative intermediately of said mandrels, and means for withdrawing said peripherally-projective means from engagement with the warp as the latter moves up to the warp-sustaining mandrel and for retaining the same in withdrawn position during the passage thereof with relation to the shuttle mechanism.
34. In a loom for circular weaving, a reel mechanism comprising means projective peripherally for carrying the warp and means projecting peripherally for carrying the woven fabric, means for advancing said reel mechanism in step movements, a mandrel for sustaining the warp, a mandrel for sustaining the woven fabric, clamping means operative with relation to said respective mandrels for clamping the warp and the woven fabric thereon during the periods between the step movements of said reel mechanism, shuttle mechanism extending and operative intermediately of said mandrels, means for withdrawing said peripherally-projective means from engagement with the warp as the latter moves up to the warp-sustaining mandrel and for retaining the same in withdrawn position during the passage thereof with relation to the shuttle mechanism, and means for bringing said fabric-carrying means into peripherally-projective position and in engagement with the woven fabric after the latter moves beyond said fabric-sustaining mandrel.
35. In a loom, a heddle mechanism comprising heddle rods having portions adapted for cam engagement, means for guiding said heddle rods in their reciprocating movement, and cam rails movable to and from
- said portions of the heddle rods to actuate the rods by the cam engagement of said rails.
36. In a loom, a heddle mechanism comprising heddle rods having lateral projections adapted for cam engagement, means for guiding said heddle rods in their reciprocating movement, cam rails arranged opposite said projections on the heddle rods, and means for operating said cam rails laterally with respect to said projections to actuate the heddle rods.
37. In a loom, a heddle mechanism comprising heddle rods having a laterally-projecting finger at their top end, means for guiding said heddle rods in their reciprocating movement, cam rails having a beveled surface operative with relation to said projecting fingers, and means for operating said cam rails in a lateral movement to and from said fingers to engage the same for the actuation of the heddle rods.
38. In a loom for circular weaving a segmental guide frame, heddle rods operatively guided in said frame and radially arranged with relation thereto, said heddle rods being provided with projections adapted for cam engagement, a segmental cam rail having a cam surface projecting with relation to said projections on the radially-arranged heddle rods, and means for moving said cam rail laterally to and from said projections on the heddle rods to actuate the latter.
39. In a loom for circular weaving, a segmental guide frame, heddle rods operatively guided in said frame and radially arranged with relation thereto, said heddle rods being provided with laterally-projecting fingers, a series of segmental cam rails concentrically arranged with relation to said segmental frame and having cam surfaces engageable with said fingers, and means for respectively moving said cam rails laterally with relation to the fingers on the heddle rods to actuate the latter.
- In witness whereof I have signed my name in the presence of the subscribing witnesses.

FREDRICK S. DICKINSON.
